UNITED STATES PATENT OFFICE.

JOHN DEAN, OF PATERSON, NEW JERSEY, ASSIGNOR OF ONE-HALF TO
JOHN F. KERR, OF PATERSON, NEW JERSEY.

DRIVING MECHANISM FOR JACQUARD-MACHINES.

SPECIFICATION forming part of Letters Patent No. 691,362, dated January 21, 1902.

Application filed July 3, 1899. Serial No. 722,690. (No model.)

To all whom it may concern:

Be it known that I, JOHN DEAN, a citizen of the United States, residing at the city of Paterson, in the county of Passaic and State 5 of New Jersey, have invented certain new and useful Improvements in Driving Mechanism for Jacquard-Machines for Looms, of which the following is a specification, reference being had therein to the accompanying 10 drawings.

The object of my invention is to provide a driving mechanism for jacquard-machines for looms which will be simple in construction, durable and cheap, and will facilitate 15 the weaving of silk goods.

The invention relates to that particular style of jacquard-machines known as a "rise-and-fall" machine.

Various constructions of a driving mechanism have been employed to operate the 20 upper and lower hook-plates of a rise-and-fall jacquard-machine, either to move them simultaneously toward and away from each other or alternately, or to move them one at a time, 25 permitting the other to remain stationary. One of the objections to most of the mechanisms known, and which my invention is meant to obviate, is the dwelling or resting for a 30 long interval of the hook-plates previous to each upward-and-downward movement. My invention reduces it to the minimum. In my invention the plates are operated so as to give the shuttle a fair opportunity to pass completely through the shed, while the opposite 35 planes thereof separate to give it unobstructed passage.

In operation my improved driving mechanism does not cause that jerky and shaky motion which causes a considerable strain on 40 the various parts of the loom. To do away with this strain as far as possible and to apply a smooth rotary motion to the driving mechanism of jacquard-machines is one of the main objects of my invention. Another 45 object accomplished by my invention is a simple and convenient means of adjustment for regulating the action or the rising and falling of the hook-plates.

My invention consists in certain parts and 50 combinations thereof, all as hereinafter is made clearly to appear, and it first will be

fully described with reference to the accompanying drawings and then will be particularly pointed out and precisely defined in the claims appended to this specification and 55 forming part thereof.

In the accompanying drawings similar letters and figures of reference indicate like parts in both figures.

In the drawings, Figure 1 is a side elevation showing my invention and illustrating the method of its operation in driving a jacquard-machine. Fig. 2 is an end view thereof.

By reference to Fig. 1 it will be seen that 65 lever-arms C and D are mounted on bearings D' and D² on the frame A and that the inner ends of the arms C and D are pivotally secured to the connecting-rods C' and C², respectively, of the upper hook-plate F' and 70 the lower F². The hook-plate F² is secured to the carriage E, and the hook-plates are guided by the guide-bars F. The guide-bars F are secured to the upper hook-plate F' and they fall with the upper hook-plate and slide 75 vertically through the arms of the carriage E. The connecting-rods C', which are connected with the inner ends of the lever C, are also pivotally connected with the upper hook-plate F', and the connecting-rods C² are piv- 80 otally connected with the arms of the carriage E, through which the rods F are adapted to slide vertically in an opening provided therein for that purpose. The outer ends of the lever-arms C and D are connected with 85 eccentrics 1 1 by the connecting-links 3 3, which are in turn connected with the eccentric-straps 4 4 of the eccentrics 1 1.

The main driving-shaft 16 is driven from the main shaft of the loom, a sprocket-chain 90 18 connecting a sprocket-wheel 15 on shaft 16 with sprocket-wheel on main shaft of the loom.

The eccentrics 1 1 and the eccentric-plates 20 and adjusting-plates 21 are bolted to the 95 eccentric-straps 4. The adjusting-plates 21 and the eccentric-plate 20 are provided with slots 22 to admit the adjusting-bolts 23, and the plates of the eccentrics also are provided with a slot 28 to allow for the shaft 16. The 100 shaft 16 is mounted in bearings 2 2. The eccentrics are located directly on the shaft 16

and revolve independently upon the same. A miter gear-wheel 5, secured to the end of the shaft 16, meshes with and turns a miter gear-wheel 6 and turns the sprocket-wheel 7, 5 from which chain 10 passes to the sprocket-wheel 9 on the eccentric-shaft 8. The sprocket-wheel 7 and miter-gear 6 are both mounted on the shaft 17. The shaft 8 works the eccentrics 12, which operate the arms B, in which 10 is mounted the cylinder G. The eccentric-rod 13 being connected with the cylinder-arm B by means of rod 14, power is thus conveyed from the main driving-shaft of the loom to the main driving-shaft of the jacquard driving mechanism. The shaft 16 and eccentrics 11 operate the lever-arms C and D, thus causing the hook-plates F' and F² to rise and fall and causing the eccentrics 12 to operate the cylinder-arms and batten B.

20 As is obvious, the adjustment of this mechanism to regulate the rise and fall of either or both of the hook-plates is very simple and easily accomplished.

With this description of my invention, what 25 I claim is—

1. In a jacquard-machine, the combination with the main frame of the machine of the driving-shaft 16 mounted in bearings at right angles with the front of the jacquard-machine, 30 the shaft 8, the shaft 17, both of said shafts running parallel with the front of the machine, the batten B, cylinder G, the eccentrics 12, driven by the shaft 8, the rod 14 connecting the batten B with the eccentric-strap 35 13, the intermeshing miter gear-wheels 5

and 6 secured to an end of shafts 16 and 17 respectively, the sprocket-wheels 7 and 9 and sprocket-chain 10 connecting the same, constructed substantially as set forth.

2. In a jacquard-machine, the upper hook-plate, the lower hook-plate, and two bifurcated levers, the arms of which are pivotally secured to the frame of the machine, in combination with a driving-shaft, located at right angles to the front of the machine, eccentrics 40 45 and eccentric-plates located directly on said shaft and revolving independently on the same, said eccentric-plates being provided with a slot for adjusting the same, eccentric-straps provided with adjusting-slots, links 50 pivotally secured to the outer ends of said lever-arms, adjusting-plates connecting said links and said eccentric-straps, rods connecting pivotally the upper hook-plate and the arms of the upper bifurcated lever, rods pivotally connecting the lower hook-plate and the arms of the lower bifurcated lever, the carriage E secured to the lower hook-plate and guide-rods secured to the upper hook-plate, and adapted to rise and fall therewith, 55 and to slide vertically through the arms of the carriage E, in openings provided therein, substantially as set forth.

In testimony whereof I affix my signature in presence of two witnesses.

JOHN DEAN.
